UNITED STATES PATENT OFFICE.

JAMES W. JONES AND THOMAS M. JERREL, OF ROCKWELL, FLORIDA.

RAIL-JOINT.

1,087,775.

Specification of Letters Patent. Patented Feb. 17, 1914.

Application filed September 9, 1913. Serial No. 788,879.

To all whom it may concern:

Be it known that we, JAMES W. JONES and THOMAS M. JERREL, citizens of the United States, residing at Rockwell, in the 5 county of Marion and State of Florida, have invented new and useful Improvements in Rail-Joints, of which the following is a specification.

The present invention relates to improvements in rail joints, and resides in the construction, combination and arrangement of parts set forth in the following specification and falling within the scope of the appended claim.

15 In the drawing: Figure 1 is a perspective view of two railway rails connected in accordance with our invention, Fig. 2 is a transverse sectional view approximately on the line 2—2 of Fig. 1, Fig. 3 is a detail central longitudinal sectional view, the rails being shown in elevation, and Fig. 4 is a top plan view of the joint member, the rails being removed.

20 Referring now to the drawings, R—R designates two rail ends, which are adapted to be connected through the medium of our improved joint. The joint comprises a base member 1 upon which the flanges of the rails 25 resting, the longitudinal edges of the base being upturned and provided with angular flanges 2 which overlie the base 1 and which have their inner faces shaped to agree with the angular upper faces of the base flanges 30 of the rails. The overlying flanges 2 terminate in vertical plates 3, the said plates being of sufficient length to permit of the 35 upper edges contacting with the underfaces of the heads of the rails.

The joint member is centrally provided 40 upon its interior with a transversely arranged partition 4, the same terminating in a head 5 which projects above the longitudinal edges of the plates 3 and which conforms in shape with the heads of the rails R. It 45 will thus be noted that the joint member provides two compartments, each shaped to correspond with the cross sectional shape of the rail, and each adapted to receive one of the ends of the rails.

50 The plates 3, adjacent the ends thereof, are provided with openings which are adapted to register with similar openings in the webs of the rails, and passing through the 55 alining openings are headed members 6 which have their shanks slotted for the reception of wedge-shaped cotter pins 7,

whereby the members 6 are effectively sustained against displacement, which, as is well known, is common to bolts provided with the usual retaining nuts, when employed in such connection. The portions of the vertical members or plates 3, provided with rail connecting elements, are vertically straight, but the central portions of the sides are enlarged for a suitable distance beyond 60 the opposite ends of the heads 5 and the partition 4, the said enlargements, which are designated by the numerals 8, being inclined gradually from the upper portions of the sides to the lower longitudinal edges thereof, and the sides 9 of the said enlargement 65 are sloped gradually outwardly and laterally to their connection with the vertically straight portions. 70

The longitudinal edges of our improved 75 rail joint member or chair are preferably notched to provide seats for securing spikes 10 which enter the ties 11, while the underface of the base member between the ties is thickened, as indicated by the numeral 11, 80 the base increasing gradually in thickness from points adjacent its sides and ends toward the center and being thickest just below the joint of the rails, which of course is the point of greatest vertical strain. 85

The rails are inserted within the joint chair from the opposite sides of the chair, and connected in the manner stated, and from the above description, taken in connection with the accompanying drawing, the 90 simplicity of the device as well as the advantages thereof will, it is thought, be perfectly apparent to those skilled in the art to which such inventions appertain without further detailed description. 95

Having thus described the invention, what we claim is:

A rail joint member comprising an integral device divided into two rail-receiving compartments, the inner faces of which each 100 conforming to the cross sectional shape of the rails and to permit of the rails resting upon its base, the partition being integrally formed with a head against which the heads of the rails abut, the side plates of the rail 105 member having their ends vertically straight and their central portion enlarged and sloping from the upper edges of the said sides to the lower edges thereof, and the sides of the enlarged portion sloping outwardly and 110 laterally to their connection with the vertical portions of the plates, the base having its

lower face centrally formed with an integrally formed longitudinally extending enlargement which gradually increases in thickness from its sides and ends to provide the greatest thickness beneath the partition and head of the rail member, means for securing the rails within the compartments of said rail members, and means co-acting with the webs of the rails and the reduced por-

tions of the sides of the rail member for securing the rails within the compartments. 10

In testimony whereof we affix our signatures in presence of two witnesses.

JAMES W. JONES.
THOMAS M. JERREL.
